UNITED STATES PATENT OFFICE

HENRY H. TALBOYS, OF MILWAUKEE, WISCONSIN, ASSIGNOR TO NORDBERG MANUFACTURING COMPANY, OF MILWAUKEE, WISCONSIN, A CORPORATION OF WISCONSIN

SPIKE PULLER

Application filed July 9, 1930. Serial No. 466,737.

This invention relates to a machine for pulling or removing spikes, nails and the like. In the form illustrated herewith it is particularly adapted for pulling railroad spikes. It 5 has for one object to provide a machine which may be readily moved from place to place and which may be used in pulling railroad spikes. Another object is to provide such a machine so equipped that it may run on the rails of a railroad and may be used to pull spikes from 10 the ties beneath it. Another object is to provide a multiple spike pulling machine by means of which two pulling elements may be used with a single mechanism. Another 15 object is to provide in connection with such a spike pulling machine a means for relieving the supporting structure of the machine of shock and jar incident to its operation and for transmitting such support directly to the 20 rails. Another object is to provide a spike pulling machine that will pull spikes without bending them, thus saving the labor necessary to straighten bent spikes.

Other objects will appear from time to time 25 in the specification and claims.

My invention is illustrated more or less diagrammatically in the accompanying drawings, wherein:

Figure 1 is a side elevation with parts 30 broken away and parts in section;

Figure 2 is a front view;

Figure 3 is a longitudinal vertical cross section on an enlarged scale, taken at line 3-3 of Figure 2;

Figure 4 is a horizontal cross section taken 35 at line 4-4 of Figure 1;

Figure 5 is a transverse vertical cross section taken at line 5-5 of Figure 1 and showing the machine raised above the rails in an 40 inoperative position;

Figure 6 is a detailed transverse vertical cross section taken at line 6-6 of Figure 1, showing a part of the track contacting member;

Figure 7 is a fragmentary side elevation 45 generally similar to Figure 1, showing the spike tongs in the raised position;

Figure 8 is a fragmentary side elevation showing the tongs separately;

Figure 9 is a fragmentary plan view on an

enlarged scale showing the top of the tongs supporting structure of Figure 8;

Figure 10 is a view similar to Figure 9, showing a modified form of tongs support;

Figure 11 is a fragmentary side elevation 55 of a detail of the frame bearing support;

Figure 12 is a transverse vertical cross section taken at line 12-12 of Figure 11;

Figure 13 is a side elevation showing a modified form;

Figure 14 is a transverse vertical cross section taken on line 14-14 of Figure 13.

Like parts are designated by like characters throughout the specification and drawings.

The machine is adapted to be mounted 65 upon and to run along a railroad although it might be mounted to run on any other road surface. In the drawings A indicates a road bed in which ties A¹ are positioned. A² are tie plates, positioned upon the ties and carrying rails A³ which are fastened to the ties by spikes A⁴ which pass through the tie plates. They extend into the ties and engage the flanges of the rails.

The machine is supported on a truck which 75 is formed of a frame. The frame itself is formed of transverse members B, B and side longitudinal members B¹, B¹ and intermediate longitudinal members B². Extending transversely between one of the intermediate 80 longitudinal members B² and one of the outside longitudinal members B¹ is a pair of shorter transverse frame members B³, B³. The forward transverse member B is preferably reinforced by a downwardly extending 85 flange B⁵. Positioned beneath the forward transverse member B is a built up transverse member formed of a pair of angles B⁶, B⁶, positioned as shown in Figure 3 facing each other, slightly separated so that they embrace 90 the downwardly extending flange of the T-shaped member B. This latter is slotted as at B⁷, B⁷ and bolts B⁸ extend through the slots B⁷ and through the upwardly extending flanges of the members B⁶.

Fastened on the under side of the members B⁶ are bearing blocks B⁹, B⁹. Extending vertically between the member B and the downward flanges of the members B⁶ are bolts B¹⁰ about which are positioned compression springs B¹¹. Toward 100

the rear of the frame and positioned on the outer longitudinal members B¹ are supporting or spacing members B¹², upon which are positioned bearing blocks B¹³. An axle B¹⁴ is journaled in the blocks B¹³ and carries flanged wheels B¹⁵. An axle B¹⁶ is journaled in the bearings B⁹.

Extending upwardly from the truck frame just described, is a super-structure comprising preferably two upright members C. They are provided with a diagonal bracing member C¹. Between them is pivoted a lever C² which is preferably strengthened or enlarged at its forward end and is provided with a hook C³ at that end. A link or connecting rod C⁴ is pivotally supported on the lever C² adjacent the hook. Adjacent the forward end of the frame is a vertically extending member C⁵ which is braced by a diagonal member C⁶. This member is attached at one end to a side frame member and extends upwardly from the truck frame and forwardly beyond it. C⁷ is a diagonal bracing member fastened also to the vertical member C⁵. Supported on the vertical member C⁵ and forming a partial inclosure and a guide for the lever C² is a box or housing formed of side members C⁸, C⁹ and slotted front members C¹⁰. The slot in this member preferably extends throughout only a part of its length. At the forward end of the truck frame are vertically extending members C¹¹ which are joined by a transverse member C¹². Together these members form a handle by means of which the truck may be positioned. C¹³ is a handle member fastened at one end to the brace C⁷ and also to the vertical member C⁵ and extending laterally beyond the truck and the parts which it carries and serving as a handle by means of which the truck may be moved. C¹⁴ is a jack positioned between the transverse members B³ of the truck frame. At its lower end it carries a contact foot C¹⁵ and at its upper end a handle C¹⁶. The jack may be manipulated to raise the truck from the rails. This position is indicated in Figure 5, in which the foot C¹⁵ is in contact with a block C¹⁷. The jack is supported in nuts C¹⁸. Positioned between the side members C⁸ and C⁹ of the housing are guides C¹⁹ which are held in place by bolts C²⁰ upon which spacers may be positioned.

D indicates generally a driving engine. An internal combustion engine has been shown but any suitable source of power might be substituted. It is sufficient for the purposes of my invention that some power source be positioned as a part of the assembly. The engine is provided with a driving wheel A which may serve also as a fly-wheel D¹. A driven wheel or pulley D² is mounted on a shaft D³ which is supported in suitable bearings D⁴. The shaft D³ also carries a pinion D⁵. The pulley D² is driven from the fly-wheel D¹ by a belt D⁶ which may be provided

with a tightening pulley D⁷ carried on links D⁸ and held in yielding contact with the belt by means of a spring D⁹. D¹⁰ is a shaft supported in bearings D¹¹, carrying preferably adjacent one end a gear D¹² which is in mesh with the pinion D⁵. A housing D¹³ normally encloses the pinion D⁵ and the gear D¹². Adjacent its opposite end the shaft D¹⁰ carries a crank D¹⁴ which has fastened to it the connecting rod C⁴. By means of the drive arrangement just described, the lever C² with its hook C³ is caused to rise and fall in response to rotation of the shaft D¹⁰ by the engine D. Other means might be provided for giving such a rising and falling motion to the lever and hook.

Fastened on one of the side frame members B¹ is a reinforcing and track contacting member E. This member, as shown, is of increased vertical thickness adjacent the forward end of the truck, being provided with a downwardly flared part E¹. A somewhat similarly shaped transverse member E² is placed across the forward end of the vehicle and it is provided with a downwardly flared or enlarged part E³. The part E³ of the member E² converges with and is joined to the forwardly extending part E¹ of the member E. It thus reinforces that member and the two together form a downwardly extending shoe which normally clears the track upon which the machine is supported. The member E¹ may form a track contacting part itself or, in the preferred form illustrated, it may have removably attached to it a contacting shoe E⁴. This shoe may be formed of three members as indicated particularly in Figure 6, and fastened by bolts E⁵ or in some other fashion, removably mounted on the member E². In this fashion the actual track contacting member may be made harder than would otherwise be possible and will thus stand more wear.

In the upper end of the member C⁶ is an enlargement F which may carry one or two upwardly extending projections F¹. In one form of the invention a member F² is positioned to the member F and to it two ring bolts F³ may be fastened. To each of these a tongs assembly may be attached in the manner to be described below. The member F² itself is removably held in position by a bolt F⁴. In a modified form of the invention as shown in detail in Figure 10, instead of the double member F² a single member F⁵ is used. It carries but a single ring bolt F³ and can thus carry only one tongs assembly. It may, however, be rotated from the position shown in full lines in Figure 10 to that shown in dotted lines in Figure 10, and thus the single tongs assembly which it carries may be moved to either side of a rail and the machine can thus pull spikes from either side of the rail.

As above stated, one or two tongs assem-

bles may be used. If one is used, it may be swung from side to side so as to pull spikes from both sides of a rail. If two are used, this is unnecessary and they may both be used together so that two operators may work on a machine, each handling one tongs assembly. The operation of the tongs is the same in either case and structurally they are substantially identical. For that reason I will describe only one.

The tongs consists of a member G which carries in its upper end an attaching means, for example, the ring G¹, to which a spring G² may be attached. The upper end of the spring may receive one end of a chain G³ which has its other end fastened to the ring bolt F³. Adjacent its upper end the member G may carry a flange or other projection G⁴ which serves as a handle or stop. On one side the member G has an inwardly facing shoulder forming member G⁵. The member G is slotted as at G⁶. Adjacent the lower end of the member G is pivoted a link G⁷ which is pivotally attached to a jaw member G⁸ which member may carry a spike engaging tooth G⁹. This tooth may be made integral with the jaw member G⁸ or removable therefrom, in which case it is held in place by a pin, screw or other attaching member G¹⁰. G¹¹ is a generally vertical member, positioned adjacent to and supported by the member G. It is provided with a handle G¹² which projects through the slot G⁶ of the member G. A spring G¹³ is fastened to the handle G¹² at one end, and at its other end, as at G¹⁴, it is fastened to the member G. This spring, when free to do so, raises the member G¹¹ and the parts which are controlled by it. The member G¹¹ is slotted as at G¹⁵ and through this slot the member G¹⁶, which is carried in the lower end of the member G and upon which the link G⁷ is pivoted, passes. At its lower end the member G¹¹ carries a jaw member G¹⁷ which has a spike contacting member G¹⁸ which is removably held in position thereon by a pin, screw or other attaching member G¹⁹. The jaw member G⁸ is pivoted upon the member G¹¹ as at G²⁰.

In the form of my invention shown in Figures 1 to 10, inclusive, the frame which carries the nail pulling device is supported at its forward end on springs so that as pressure is put on the device when spikes are pulled, the frame is somewhat depressed with regard to the truck frame and the track contacting shoe is brought into contact with the track and thus the actual strain and shock due to the spike pulling operation is not transmitted to the truck frame or its bearings and the wheels which carry it, but is borne by the track contacting shoe. As shown particularly in Figures 1 and 2, the cushioning arrangement is applied only to the bearings of the forward axle, that is the axle adjacent the spike pulling assembly, and

the bearings are beneath the cushioning arrangement or springs, the frame being above the axle.

In the form illustrated in Figures 11 and 12, a modified frame cushioning arrangement is shown. In it the side frame member is carried below the axle and the cushioning construction may be applied to all four bearings, that is to say, it may be applied to the front and rear axles and to each bearing which supports the axle. This may require a modification in the frame construction. The frame member H to which the bearing B⁹ of the axle B¹⁶ is attached, is positioned below the bearing B⁹ and that bearing is fastened to the frame by bolts H¹, H¹ which pass through the flanges of the frame member H and through suitable parts of the bearing B⁹. Springs H² are positioned above the bearing and carry the load of the frame and associated parts. The compression of the springs may be varied by adjustment of the nuts H³.

By reason of the somewhat modified frame construction made necessary with the changed axle supporting arrangement, instead of the member E, a similar member I is used. This member serves the same purpose as the member E but is merely of different shape. To it a modified track contacting shoe I¹ is removably attached by means of bolts I². I have shown the modified form of support in Figures 11 and 12, as applied to the forward axle. It might be so applied and it might also be applied to both axles. In the latter case, the details of construction would be almost identical with those shown for the forward axle and the frame member would preferably be positioned beneath the axle bearing support. In the form illustrated in Figures 13 and 14 the machine as a whole is the same as that shown in the earlier figures. A modified form of driving or moving arrangement is used, however. Instead of pushing or pulling the machine by hand, a crank and sprocket arrangement is shown, by means of which it is driven.

To one of the forward supporting wheels B¹⁷ members J are fastened. These members are joined to and support a sprocket J¹. In place of the laterally extended handle bar C¹³ a shaft J² is used. It may occupy generally the same position as that occupied by the handle C¹³ and that handle bar itself might be used, but I prefer to use the shaft J² which extends laterally preferably a lesser distance and is preferably situated somewhat higher. Upon the shaft J² is rotatably mounted a driving sprocket J³. Cotter pins J⁴, J⁴ hold it in proper position on the shaft J² and washers J⁵, J⁵ may also be provided. Attached to and preferably formed integral with the member J³ is a wheel J⁶ having an outwardly extending handle J⁷. A chain J⁸ is positioned about the member J³ and

the sprocket J^1 . By rotation of J^3 the sprocket J^1 is rotated. This rotation, of course, rotates the wheel B^{17} and moves the machine as a whole forward or back, depending on 5 the direction of rotation of the member J^3 . The crank is so geared to the driving wheel, that is, the wheel B^{17} , by the sprockets that one revolution of the crank will carry the machine the exact spacing of the ties.

10 It will be understood that while I have herewith shown and described a practical operative device, nevertheless many changes might be made in the size, shape, number and disposition of parts without departing materially from the spirit of my invention and 15 I wish, therefore, that my showing be taken as in a sense diagrammatic.

Particularly, my machine might be driven by any suitable power source, whether that 20 power source is mounted upon the machine or not.

Throughout the specification where I have referred to the "forward end" of the machine, I mean that end which carries the spike pulling mechanism. For the sake of convenience this is referred to as the "forward end". Obviously, of course, the machine may be moved in either direction and therefore in one sense the spike pulling assembly might be considered 25 to be at the forward end of the truck and in another sense at the rear end. The phraseology used is consistent throughout and is adopted merely for convenience. As I have used the expression "forward end", the end 30 which appears to the right in Figures 1, 4, 35 7 and 11 is meant.

The use and operation of my invention are as follows:

The machine when it is to be used is preferably put upon the rails and is moved along them to the place where it is to be put into operation. In being placed upon the rails, it may be moved by hand or it may be moved partly by the jack arrangement which is illustrated in its operation in Figure 5. The jack 40 is positioned fairly in the point of balance of the machine and with little or no outside effort the machine may be balanced and turned on the jack. The manner of attachment of the member C^{15} on the screw C^{14} is such that when the machine is raised upon it 45 it may be rotated. Thus it may be turned completely about or otherwise manipulated.

When the machine is in proper position 50 on the track and it is desired to use it to pull spikes, the engine is set in operation and through the gearing described above, the crank D^{14} is set in motion and by means of the connecting rod C^4 it causes the lever C^2 55 to rise and fall. This movement takes place constantly so long as the power source is in operation and connected so as to drive the shaft D^{10} which carries the crank D^{14} . If a spike is to be pulled, an operator takes one 60 of the tongs and usually by means of the

handle G^{12} depresses it. Also by pressing down on the handle G^{12} the lower member G^{11} of the tongs is depressed against resistance of the spring G^{13} . Thus the jaws of the tongs are moved apart and they may be manipulated to engage a spike. The force of the spring G^{13} is sufficient to raise the member G^{11} when it is free to do so, and thus to tighten the jaws on the spike. The operator then moves the tongs so that the projection G^5 70 is engaged by the hook C^3 of the lever C^2 . Since this lever is moving up and down, as soon as the member G^5 is engaged by the hook, it and the tongs will be raised. The member G^5 being on the main portion G of the tongs, the two spike engaging jaws are forced positively together and as the tongs assembly goes up, the spike is pulled straight out. As soon as it has been removed, the operator may move the tongs out of engagement with the hook C^3 and the spring G^{13} 75 then moves the jaws apart to release the spike. If two tong assemblies are used, they are operated as described and two operators may work together, alternating so that the spike is drawn first from one side and then from the other.

As above pointed out, in order to relieve the truck frame from shocks and jars incident to operation of the spike pulling machine, the spike puller proper is mounted on an auxiliary supporting assembly, which is mounted for cushioning movement with respect to the truck frame. Thus when tension first comes on a tongs as a spike is being drawn, the movable support carrying pulling mechanism is depressed in opposition to the spring which normally holds it in a somewhat raised position, so as not to interfere with movement of the machine along the rails by dragging thereon, and the contact member E^4 is brought into contact with the rail A^3 . From then on, the strain of the pull is transmitted directly through the contact member to the rail and is not borne by the truck frame and thus the truck frame as a whole and its wheels and their bearings particularly, are cushioned from shocks and jars. As soon as tension on the spike pulling tongs is released, the frame regains its normal position under the influence of the springs B^{11} . This yielding action for cushioning the frame will occur whether merely the forward end of the machine is mounted on a cushioning support, as indicated in Figures 1 to 10, inclusive, or if the entire frame and all of the bearings are so arranged, as indicated in the forms shown in Figures 11 and 12.

When the driving mechanism as illustrated in Figures 13 and 14 is used, the machine, instead of being pushed or pulled by hand, will be driven by the crank and sprocket arrangement shown in those figures. Most railroads now have a practically uniform spacing of ties and thus one sprocket ratio will be 125 130

satisfactory for practically universal use. That ratio is such that a single rotation of the crank wheel will move the machine the exact distance from one tie to the next so that 5 when it has been used at one tie a single rotation of the crank will positively move it to the next position of use and it may be immediately used without the necessity of slight adjustments or hand pushing or 10 pulling. This driving device allows the machine to be stopped and started more rapidly than when it must be moved by hand and permits its more accurate spacing. Thus the output of the machine and the quantity 15 of spikes pulled in a given time is increased.

I claim:

1. In a movable spike pulling machine, a vehicle truck frame, axles and wheels supporting said frame, a spike pulling assembly positioned upon said frame, a support therefor movable with respect to the running gear of said frame, cushioning elements adapted normally to hold said support in one position and adapted to yield under pressure 25 to permit movement of said support into another position, a road surface contacting member carried by said support adapted when the support yields under pressure to contact the road surface, said spike pulling 30 assembly including a lever and means for moving the same up and down, a nail engaging tongs adapted to be moved into engaging contact with a nail and to be moved into contact with said lever, whereby said 35 tongs is raised, a spring support for said tongs adapted normally to hold the tongs in a raised position, the tongs including a main member carrying a part adapted to engage said lever and carrying a second part movable with relation thereto, a spring adapted 40 to hold the parts in one position, and a handle whereby the parts may be moved against the opposition of the spring into another position, one of said parts carrying a fixed spike 45 engaging member and a movable spike engaging member, a link connecting said movable spike engaging member to the other of said parts, whereby relative movement of the two main parts is effective to move the spike 50 engaging jaws toward and from each other.
2. In a spike handling machine, a wheeled vehicle, a spike handling assembly positioned thereon and driving means for moving the machine as a whole, including a crank, and 55 so proportioned that a single rotation of the crank will move the machine the exact distance necessary.

3. In a railroad spike pulling machine, a vehicle adapted to run along rails, a spike 60 pulling assembly, a driving means for said vehicle, including a crank, said driving means so proportioned that a single rotation of the crank will move the machine from one tie to the next.
4. In a railroad spike pulling machine, a

supporting frame, a tongs assembly yieldingly and laterally flexibly mounted upon the supporting frame, manually operable means for positioning said tongs assembly in spike pulling position, and means for imparting upward movement to said tongs assembly when so positioned. 70

5. In a railroad spike pulling machine, a supporting frame, a tongs assembly yieldingly and laterally flexibly mounted upon the supporting frame, manually operable means for positioning said tongs assembly in spike pulling position, and means for imparting upward movement to said tongs assembly when so positioned, including a lifting member 75 and means for actuating it.

6. In a railroad spike pulling machine, a supporting frame, a tongs assembly yieldingly and laterally flexibly mounted upon the supporting frame, manually operable means for positioning said tongs assembly in spike pulling position, and means for imparting upward movement to said tongs assembly when so positioned, including a lifting lever 80 pivoted at a point remote from the tongs and lying in generally horizontal position, and means associated with the end of the lever adjacent the tongs for lifting it.

7. In a railroad spike pulling machine, a supporting frame, a tongs assembly yieldingly and laterally flexibly mounted upon the supporting frame, manually operable means for positioning said tongs assembly in spike pulling position, and means for imparting upward movement to said tongs assembly 95 when so positioned, including a lifting lever pivoted at a point remote from the tongs and lying in generally horizontal position, and means associated with the end of the lever adjacent the tongs for lifting it, including a 100 motor, a rotary drive member actuated by said motor, and a link pivoted eccentrically in relation thereto at one end and secured at the other end to the lever.

8. In a nail pulling machine for railway spikes and the like, a carriage movable along a track, supporting wheels for said carriage, adapted to ride on the rails of such track, a tong supporting frame extending upwardly above a rail of said track and generally 110 vertically aligned therewith and mounted on and movable with said carriage, and a tongs assembly flexibly suspended from said support, said suspension being adapted to permit free lateral movement of said tongs assembly 115 in any direction, said tongs assembly including a plurality of nail gripping elements, means for positioning said nail gripping elements in gripping relationship to a nail head and means for imparting a sharp upward 120 movement to the tongs assembly.

9. In a nail pulling machine for railway spikes and the like, a carriage movable along a track, supporting wheels for said carriage, adapted to ride on the rails of such a track, 130

- 5 a tong supporting frame extending upward-
ly above a rail of said track and generally
vertically aligned therewith and mounted on
and movable with said carriage, and a tongs
assembly flexibly suspended from said sup-
port, said suspension being adapted to per-
mit free lateral movement of said tongs
assembly in any direction, said tongs assem-
bly including a plurality of nail gripping
elements, means for positioning said nail
gripping elements in gripping relationship
to a nail head and means for imparting a
sharp upward movement to the tongs assem-
bly including a lever mounted upon the car-
riage for movement about an axis longitudi-
nally substantially spaced from the tong sup-
porting frame, and an actuating connection
between the opposite end of said lever and
the tong supporting frame.

10 10. In a nail pulling machine for railway
spikes and the like, a carriage movable along
a track, supporting wheels for said carriage,
adapted to ride on the rails of such a track,
a tong supporting frame extending upward-
ly above a rail of said track and generally
vertically aligned therewith and mounted on
and movable with said carriage, and a tongs
assembly flexibly suspended from said sup-
port, said suspension being adapted to per-
mit free lateral movement of said tongs as-
sembly in any direction, said tongs assembly
including a plurality of nail gripping ele-
ments, means for positioning said nail grip-
ping elements in gripping relationship to a
nail head and means for imparting a sharp
upward movement to the tongs assembly in-
cluding a lever mounted upon the carriage
for movement about an axis longitudinally
substantially spaced from the tong support-
ing frame, and an actuating connection
between the opposite end of said lever and the
tong supporting frame, including an abutment
member on said lever and an opposed abut-
ment on said tongs assembly, and manually
operable means for moving said abutment
into vertical alignment.

15 12. In a nail pulling machine for railway
spikes and the like, a carriage movable along
a track, a tong supporting means extending
upwardly from said carriage and generally
vertically aligned with a rail of said track,
and a tongs assembly flexibly suspended from
said support, said suspension being adapted
to permit free lateral movement of said tongs
assembly in any direction, said tongs assem-
bly including a plurality of nail gripping
elements, means for positioning said nail grip-
ping elements in gripping relationship to a
spike head, and means for imparting a sharp
upward movement to the tongs assembly
when the tongs are in gripping relation-
ship to such spike head.

20 13. In a nail pulling machine for railway
spikes and the like, a carriage movable along
a track, a tongs assembly suspended from
said carriage, and suspension means for said
tongs assembly, said suspension means being
yieldingly extensible and freely flexible.

25 14. In a nail pulling device for railway
spikes and the like, a carriage movable along
a track, a tongs supporting means mounted
on and movable with said carriage and gen-
erally vertically aligned with a rail of said
track, a tongs assembly suspended from said
supporting means, and suspension means for
said tongs assembly, said suspension means
being yieldably extensible and freely flexible,
and means mounted on and movable with said
carriage for imparting to said tongs assem-
bly a sharp upward movement, an actuating
connection between said last mentioned
means and the tongs assembly, including
abutments on said means and said tongs as-
sembly adapted to be vertically aligned with
each other, and manual means for moving
said tongs assembly into and out of actuating
relationship with said movement imparting
means.

30 15. In a nail pulling device for railway
spikes and the like, a carriage movable along
a track, a tongs supporting means mounted
on and movable with said carriage and gen-
erally vertically aligned with a rail of said
track, a tongs assembly suspended from said
supporting means, and suspension means for
said tongs assembly, said suspension means
being yieldably extensible and freely flexible,
and means mounted on and movable with said
carriage for imparting to said tongs assem-
bly a sharp upward movement, an actuating
connection between said last mentioned
means and the tongs assembly adapted to be
vertically aligned with each other, and man-
ual means for moving said tongs assembly
into and out of actuating relationship with

35

said movement imparting means, and means operable against the track for preventing downward movement of the carriage in response to upward movement of the tongs.

- 5 16. In a nail pulling device for railway spikes and the like, a carriage movable along a track, a tongs supporting means mounted on and movable with said carriage and generally vertically aligned with a rail of said
10 track, a tongs assembly suspended from said supporting means, and suspension means for said tongs assembly, said suspension means being yieldably extensible and freely flexible, and means mounted on and movable with said
15 carriage for imparting to said tongs assembly a sharp upward movement, an actuating connection between said last mentioned means and the tongs assembly adapted to be vertically aligned with each other, and manual means for moving said tongs assembly into and out of actuating relationship with said movement imparting means, and means operable against the track for preventing downward movement of the carriage in
20 response to upward movement of the tongs, said means including a member located adjacent the tongs and spaced closely above a rail of the track.

Signed at Milwaukee county of Milwaukee
25 and State of Wisconsin, this 2nd day of July 1930.

HENRY H. TALBOYS.
